FOREIGN PATENT DOCUMENTS

EP 0 633 859 4/1992

FIG. 1 is a perspective view of a first embodiment of a closure for a container showing our new design;

FIG. 2 is a top view thereof;

FIG. 3 is a side view thereof;

FIG. 4 is a perspective view of a second embodiment thereof;

FIG. 5 is a top view thereof;

FIG. 6 is a side view thereof;

FIG. 7 is a perspective view of a third embodiment thereof;

FIG. 8 is a top view thereof;

FIG. 9 is a side view thereof;

FIG. 10 is a perspective view of a fourth embodiment thereof;

FIG. 11 is a top view thereof; and,

FIG. 12 is a side view thereof.

The bottom of the closure is devoid of surface ornamentation, is not shown in the drawing and forms no part of the design.

The broken lines in the drawings illustrate environmental structure that forms no part of the claimed design.
